(57) **CLAIM**

The ornamental design for a drinking mug with stirring apparatus, as shown and described.

DESCRIPTION

FIG. 1 is a top front perspective view of a drinking mug with stirring apparatus showing my new design;

FIG. 2 is an enlarged top plan view thereof, where the lid is rotated 90 degrees from that shown FIG. 1;

FIG. 3 is a bottom plan view of FIG. 1;

FIG. 4 is an exploded cross-sectional view taken along 4-4 of FIG. 1; and,

FIG. 5 is an enlarged plan view thereof with the lid removed for ease of illustration.
